UNITED STATES PATENT OFFICE.

ROBERT W. KRUSE, OF INDIANAPOLIS, INDIANA.

PROCESS OF FORMING CONNECTING COLLARS FOR RADIATORS AND FEED DOORS.

Application filed August 16, 1919. Serial No. 317,958.

To all whom it may concern:

Be it known that I, ROBERT W. KRUSE, a citizen of the United States, and a resident of Indianapolis, county of Marion, and State of Indiana, have invented a certain new and useful Process of Forming Connecting Collars for Radiators and Feed Doors; and I do hereby declare that the following is a full, clear, and exact description thereof, reference being had to the accompanying drawings, in which like numerals refer to like parts.

This invention relates to a process of forming connecting collars for radiators and feed doors on furnaces and like constructions which may become heated to a high degree. Difficulty has been experienced in using the common construction of riveting a cast iron connecting collar to the walls of the furnace, because of the different expansions of the two metals under the heat, which will cause slight separation and warping and permit leakage, besides increasing the cost and time of production. The process of forming the connecting collars, as will be hereinafter more specifically shown and described, will permit of its complete formation from the same metal as the walls are composed of, whereby the complete construction can be formed from a simple stamping and welding process at the minimum of cost.

One of the advantages of this construction is that the bolts for securing the connection are placed away from the furnace wall, whereby they will not be exposed to the heat as in the ordinary construction where the connections are bolted directly into or adjacent the wall.

Referring to the drawings, which are made a part of this application, Fig. 1 is a perspective view showing the completely formed connecting collar. Fig. 2 shows a portion of the metal used in the walls of the furnace after it has been cut. Fig. 3 is a section taken on the line 3—3 of Fig. 2 showing the side walls of the collar bent outwardly. Fig. 4 is a front elevation showing the same formation as in Fig. 3. Fig. 5 is a plan view looking down upon a section of the metal forming the top and bottom of the collar. Fig. 6 is a front elevation of the same as shown in Fig. 5. Fig. 7 shows a section of a furnace with the top section in place. Fig. 8 is a front elevation showing a furnace with

the completed collar formed thereon. Fig. 9 is a side elevation of the same as shown in Fig. 8.

The process of forming the connecting collar from the same sheet of metal as is used in forming the walls of the furnace, consists in taking the blank sheet 10 and cutting therein a downwardly extending slot 11 from the top thereof, and a cross slot 12 at right angles to the slot 11 and connecting with the bottom thereof, and the bolt holes 13 on each side of the vertical slot 11. The portions 14 of the metal 10 are then bent outwardly and perpendicular to the body portion so as to be substantially parallel and then bent nearly at right angles to form the flanges 15, substantially parallel to the body portion and at right angles to the parallel portions 14. This operation completes the formation of the side sections of the completed connecting collar.

The top and bottom sections 16 are formed from similar sheet metal. Each section 16 is stamped out and the holes 17 formed therein, and then the flange 18 is turned at right angles thereto as shown in Fig. 5. The sheet metal 10 is then formed into a furnace, usually circular in cross section, and the sections 16 mounted on the top and bottom of the side portions 14 and welded thereon or otherwise suitably secured by creasing, crimping or the like, whereby the completed collar is formed as shown in Figs. 1, 7, 8 and 9. This simple process enables such a collar to be formed so as to eliminate any riveting, or the mounting of collars formed of other metals, whereby any shrinkage or warping may occur from the high temperature of the furnace. Aside from this a much neater and cleaner appearance is given to the job, and an appreciable amount of labor is saved.

The collar flanges 15 and 18 thus formed are positioned in a relatively cool portion of the furnace construction and to the same may be secured the usual door plate and furnace door, which ordinarily is of a different material than sheet metal, or which has a different co-efficient of expansion. Thus by positioning the securing flanges 15 and 18 away from the greatest heat of the furnace, the door plate and furnace door may be secured in the doorway and to the flanges where the temperature thereof will not em-

phasize the difference in the expansion coefficient and the leakage usually resulting therefrom.

The invention claimed is:

- 5 The process of making doorway collars on furnaces having a sheet metal body portion, consisting of cutting the sheet metal vertically with the wall substantially the same length as the width of the collar, cutting said metal perpendicularly to said beforementioned cut, bending the cut portion of said metal outwardly away from said wall so as to form projecting and parallel side portions of said collar, bending the edges of said por-

tions at right angles so as to form connecting flanges, stamping top and bottom sections, and bending a portion thereof outwardly to form corresponding flanges and securing said top and bottom sections to said side portions and body portion so as to completely enclose the opening formed therein and provide a flange face to which a doorway plate and door may be secured in spaced relation to said wall.

In witness whereof, I have hereunto affixed my signature.

ROBERT W. KRUSE.
